UNITED STATES PATENT OFFICE.

JOHN BERNHARDT RUDOLPH, OF JERSEY CITY, NEW JERSEY.

SANITARY SHAVING-MUG.

1,072,994.

Specification of Letters Patent. Patented Sept. 9, 1913.

Application filed February 4, 1911. Serial No. 606,519.

To all whom it may concern:

Be it known that I, JOHN BERNHARDT RUDOLPH, a citizen of the United States, and a resident of Jersey City, in the county 5 of Hudson and State of New Jersey, have invented a new and Improved Sanitary Shaving-Mug, of which the following is a full, clear, and exact description.

My invention relates to a new and improved form of shaving mug, and an object 10 of the invention is to provide a sanitary shaving mug so shaped and constructed that water and injurious acids in the soap will readily drain off the soap into a separate 15 water reservoir.

A further object of my invention is to provide a handle to such a device, so constructed and positioned that it cannot readily be broken from the body of the mug.

20 A further object of my invention is to construct the mug, that the preparation of the lather is done from the side of the mug and not from the top as is common in the ordinary form of shaving mugs.

25 A further object of my invention is to provide a cup having a scraping surface, the outline of which is substantially the configuration of part of the brush and so disposed and arranged that the surplus lather 30 will drop into the water reservoir and not back on the soap.

A still further object of my device is to provide means whereby the surplus water about the soap will readily be drawn off, 35 leaving the soap dry.

Another object of my invention is to so 40 arrange the relative positions of the soap-containing compartment and the hot water compartment, that access may be gained to the soap-containing compartment without passing the brush through or into the hot water compartment.

With the above and other objects in view, as will more fully hereinafter appear, the 45 present invention consists in certain novel details of construction and arrangement of parts hereinafter fully described, illustrated in the accompanying drawings, and more particularly pointed out in the appended 50 claims.

Reference is to be had to the accompanying drawings, forming a part of this specification, in which similar characters of reference indicate corresponding parts in all 55 the figures, and in which—

Figure 1 is a perspective view looking

down from the front and showing a preferred embodiment of my invention; Fig. 2 is a similar view but looking down from the rear of the mug; and Fig. 3 is a transverse 60 sectional view taken vertically through the mug.

In the device as disclosed, I have shown a hollow cup or mug, preferably of a general cylindrical form having a rear portion 1 65 and a front portion 2. The rear portion is recessed at 3 on opposite sides of a medial line, which recesses unite within the rear wall of the mug to leave part of the wall in the form of a handle 4, which handle will of 70 course be in the plane of the curvature of the rear of the mug, such arrangement permitting the ready packing of a number of mugs on a shelf or in a box without the possibility of the projecting handles breaking 75 off. This arrangement of depressed handle will keep the hand out of contact with the lather which may overflow from the cup, thereby preventing the hands from coming in contact with the lather or contacting with 80 the upper edge of the mug.

Interiorly, the mug is divided by a transverse partition 5, which extends from the upper edge 6 to a short distance above the bottom 7 of the mug. This partition has a 85 centrally-disposed opening 8 extending from the upper edge 6 and converging downward at an angle to meet the curved bottom 9 of the soap receptacle. This soap receptacle occupies substantially one-half of the mug 90 in rear of the transverse partition 5, and comprises a downwardly and inwardly-inclined back surface 10 merging into a substantially U-shaped bottom surface 11, which occupies the space between the back portion 95 10 and the spaced-apart projections formed by the recess 8 in the partition 5. The back 10 is preferably flat and has a circular recess 12 disposed centrally therein, and has a number of radiating depressions 13 extending diametrically outward from the recess 12 to the circular edge of the back 10. These depressions afford means for draining the water and acid from the soap, which soap fits between the partition 5 and the 105 back 10, and is prevented from sliding into the water reservoir 14 by said partition.

Diametrically opposite the center of the back 10 and in a line with the opening 8 between the parts of the partition 5, the front 110 side 2 of the mug is recessed, to form a brush-receiving aperture 15 formed by curv-

ing the upper edge 6 downwardly to a position just above the horizontal plane containing the lowest point of the bottom 9 of the soap receiving compartment so that the overflowing of the water reservoir will not flood the soap-containing compartment. The lower part of the curvature of this opening substantially conforms to the configuration of the side of a brush, so that the brush can 10 rest upon the lower edge 16 and will extend into the mug over the water compartment 14, to contact with the cake of soap in the soap-containing compartment. This edge 16 may also be used as a scraping edge to remove the surplus lather which may adhere 15 to the sides of the brush. It will be seen that by this arrangement it is not likely that the lather will rise above the upper edge of the mug to overflow, and, further, it will be seen that any water left on the soap will 20 drain down into the water compartment 14, thereby leaving the soap clean and dry, and, at the same time, there is afforded a reservoir of water in the space 14, to again wet 25 the brush should a further lather be desired.

As the water is not left in contact with the soap but is drained off, the possibility of dissolving the soap by carelessness in leaving the soap in contact with water, is 30 eliminated. Further, by the arrangement of the curved bottom 9, it is possible to use not only soap but also shaving powder in the mug. Further, it is seen that there are no sharp points or corners in which dirt 35 may collect, the whole device being formed substantially of wide curved surfaces, which may readily be cleaned by merely holding the mug under running water.

Many changes could be made in the above 40 construction and many apparently widely different embodiments of this invention could be made without departing from the scope thereof.

It is intended that all matters contained 45 herein, in the above description or shown in the accompanying drawings, shall be interpreted as illustrative and not in a limiting sense. It is also to be understood that the language used in the following claims 50 is merely intended to cover all the generic and specific features of the invention herein-described and all statements of the scope of the invention, which, as a matter of language, might be said to fall therebetween, and that materials, sizes and relativities of 55 parts are non-essential, except as called for in the claims.

Having thus described my invention, I

claim as new and desire to secure by Letters Patent:

1. A shaving mug having a centrally-disposed vertical partition to form a water-receiving compartment and a soap-receiving compartment, the bottom of said soap-receiving compartment being positioned above 60 the bottom of said water-receiving compartment, whereby water will readily drain from the soap-receiving compartment to the water-receiving compartment, said partition being recessed from its upper edge convergently downward to permit access to said soap-receiving compartment, the side of said water-receiving compartment being recessed 65 in line with the recess in said partition, whereby access may be obtained to said soap-receiving compartment from the side of the mug.

2. A shaving mug having a flat bottom and a vertically disposed partition therein forming a water-containing and a soap-containing compartment, said soap-containing compartment having a solid bottom extending above the bottom of said water-containing compartment to render the mug stable, the rear wall of said soap-containing compartment increasing in cross section from 80 the top to said solid bottom, said rear wall and solid bottom having a pair of spaced apart vertically disposed recesses uniting to form a handle within the circumscribing 85 outline of said mug, said rear wall reinforcing the portion of the mug weakened by said recesses.

3. A shaving mug having a partition therein to form a water-containing and a soap-containing compartment, said soap-containing compartment having a substantially U-shaped bottom surface and a downwardly and inwardly-inclined back surface, said partition having a centrally disposed recess 95 therein extending from the top thereof to the bottom of said soap-containing compartment affording access thereto and forming spaced apart projections to retain the soap in the soap-containing compartment, said bottom and back surfaces maintaining the soap in a vertical position irrespective of its size.

In testimony whereof I have signed my name to this specification in the presence of 110 two subscribing witnesses.

JOHN BERNHARDT RUDOLPH.
